UNITED STATES PATENT OFFICE.

JOSEPH ASKINS, OF LIMA, OHIO.

APPARATUS FOR THE MANUFACTURE OF WATER-GAS.

SPECIFICATION forming part of Letters Patent No. 478,305, dated July 5, 1892.

Application filed January 9, 1892. Serial No. 417,580. (No model.)

To all whom it may concern:

Be it known that I, JOSEPH ASKINS, a citizen of the United States, residing at Lima, in the county of Allen and State of Ohio, have 5 invented new and useful Improvements in Apparatus for the Manufacture of Gas, of which the following is a specification.

This invention relates to apparatus for the manufacture of water-gas; and it consists 10 in a gas-generator in which are located refractory gas-superheating retorts that communicate with the interior of the generator on one hand and with a water seal, a washer, or a holder on the other; also, in combination 15 with a water-gas generator of steam-superheating pipes or passages placed in the refractory generator-lining and arranged to deliver superheated steam beneath the generator-grate, and, further, in the construction, 20 arrangement, and combination of parts in a gas-generator, as hereinafter more fully described, and then pointed out in the claims.

In the annexed drawings, illustrating the invention, Figure 1 is a sectional elevation of 25 my improved apparatus for making water-gas. Fig. 2 is a plan of the gas-superheating retorts.

Referring to the drawings, the numeral 1 designates an iron or steel shell which forms 30 the outer wall of the gas-generator. This generator is provided with a lining 2, of fire-brick or other refractory material, and has a grate 3 and self-sealing doors 4, 5, and 6, as shown. The door 4 is arranged to give access to the space below the grate-bars for the purpose of cleaning out ashes and cinders and also to serve as an air-inlet when needed. The door or doors 5 above the grate give access to the generator when it is necessary to 40 clean out the clinkers from the grate-bars and from the side walls, and these doors also serve for use in kindling the fire. The door 6 is located in the upper part of the generator for use in charging the apparatus and replenishing the fuel.

For the purpose of providing an economical supply of superheated steam for use in the manufacture of water-gas; and at the same time to protect the steam-pipes from 50 damage by a close contact with fire, I place horizontally in the generator-lining or inner fire-brick wall tubular steam-superheaters 7,

that are provided at their ends with stuffing-boxes 8, located on the outside of the generator-shell. These tubular steam-superheaters 55 7 afford passages and protecting coverings or casings for steam-pipes 9 and 10, that are extended through said casings and their stuffing-boxes, as shown. This construction not only protects the steam-pipes 8 and 9 from injury 60 by direct contact with the fire or heated fire-brick; but in case the inclosed steam-pipes become defective or damaged in any way they can be readily removed and replaced without injury to the generator-walls. Steam is admitted into the pipes 9 and 10 at the point 65 11 from any convenient source, and while passing through said pipes, inclosed in the superheaters 7, it becomes thoroughly dried and superheated before entering a pipe 12, by 70 which it is discharged into the generator ash-pit at a point below the grate-bars. This pipe 12 may be provided with a hand-valve 13 for controlling the admission of steam into the generator. 75

The several sections of steam-pipes 9, 10, and 12 may be connected by suitable bends, elbows, or couplings 14 outside the generator-walls.

Above and in close proximity to the bed of 80 incandescent coke in the generator are supported any desired number of parallel retorts or superheaters 15 and 16, that are preferably cylindrical in form and composed of fire-clay or other suitable refractory material. 85 Although I have shown only two of these retorts in the form of apparatus illustrated, it is obvious that there may be more, if desired. The ends of these retorts are inserted into openings formed in the fire-brick lining 2, 90 and communicate through openings in the shell 1 with cast-iron T's or couplings 17, 18, and 19, secured to the outside of the generator. The coupling 17 connects two adjacent retorts at one end in such a manner as to establish communication between them. The coupling or couplings 18 connect the first retort of the series with the interior of the generator above the bed of fuel, and the coupling 19 connects the last retort of the series 100 with a pipe 20, leading to a washer, water seal, or holder, as hereinafter described.

At the top of the gas-generator is a purge-valve 21 for use in producing a draft when it

becomes necessary to reheat the generator in the intervals between the runs of gas. The retort-coupling 19 is provided with a similar purge-valve 22 for use in heating the retorts 5 rapidly when required. These valves 21 and 22 are also safety-valves, and are so arranged that a gas-pressure of one pound in the generator will raise either or both of them, thereby relieving the pressure. Each valve is provided with a suitable operating-lever 23, by which the valve can be raised or opened at will, the closing of the valve being effected by gravity when the lever is released.

The water-gas generator is charged with 15 coke to a point immediately below a passage or opening 24, through which the retorts 15 and 16 communicate with the interior of said generator. After the apparatus has been 20 properly heated water-gas is made by admitting superheated steam through the pipes 9, 10, and 12 into the lower part of the generator below the grate, whence it passes upward through the body of incandescent coke, and is thereby decomposed and converted into 25 gas. The gas thus produced passes through the opening 24 and couplings 18 into the retort or gas-superheater 15, and thence through the coupling 17 into the retort or superheater 16, and while it remains in these superheating-retorts it is converted into a fixed gas by 30 the intense heat to which the refractory retorts are subjected. From the retort 16 the gas is conveyed through the coupling 19 and pipe 20 to a washer or to any suitable gas-holder, as may be preferred.

As shown in the drawings, the exit end of the pipe 20 may be submerged in a water seal formed by a body of water contained in a closed tank 25, which is provided with a gas-exit pipe 26, that may lead to any suitable gas-holder (not shown) or to the place of consumption. In passing through the water seal or washer the gas is cleansed from lamp-black and dirt or impurities, and thus made ready 45 for immediate use, if desired.

It will be observed that in this apparatus there is no superheater or regenerator filled with checker-work of fire-brick or other refractory material, which must be heated at 50 the expense of the fuel in the generator and requiring a strong blast to reheat the generator between each run of gas.

In my apparatus the retorts 15 and 16 serve as gas-superheaters, and being close to the coke-fire are always hot, which enables the 55 gas-runs to be continued from two to three times longer than in any other apparatus now in use.

Instead of employing a blower for use in creating a draft when reheating the generator 60 between the runs of gas, I open the doors 4 and 6 slightly and raise the valve 21, thus causing a draft which soon reheats the generator without the waste of much fuel. If the retorts 15 and 16 need a little extra heat, the 65 valve 21 is closed and the valve 22 opened, which allows all the heat to pass through the retorts, thus heating them very rapidly and with a small consumption of fuel as compared with the reheating of other generators. 70

What I claim as my invention is—

1. In an apparatus for the manufacture of water-gas, the combination of a gas-generator having a purge-valve in its upper part, horizontal parallel gas-superheating retorts located in the generator and communicating with each other and with the interior of the generator above the bed of fuel, a purge-valve connected with one of said retorts, a gas-exit pipe leading from said gas-superheating retorts, and steam-pipes communicating with the lower part of the generator below its grate, substantially as described. 75

2. In an apparatus for the manufacture of water-gas, the combination of a generator having a purge-valve in its upper part and provided with a grate and with self-sealing doors located above and below the grate, horizontal parallel gas-superheating retorts located in the generator above the bed of fuel and communicating with each other and with the interior of the generator, a purge-valve connected with one of said retorts, a gas-exit pipe leading from the retorts, and steam-pipes communicating with the lower part of the 95 generator below its grate, substantially as described. 80

In testimony whereof I have hereunto set my hand and affixed my seal in presence of two subscribing witnesses.

JOSEPH ASKINS. [L.S.]
